AIR CONDITIONER

Harry Howell Hays, 2530 San Diego St., El Paso, Tex.

Filed Sept. 29, 1958, Ser. No. 763,944

9 Claims. (Cl. 183—14)

My invention relates to air control devices for household use, and this control applies not only to the circulation of the air, but also to the cooling and/or humidifying thereof.

Householders recognize the benefits of air conditioning but for various reasons many do not utilize it, and they depend on ventilation of the house through open windows.

As outer atmospheric conditions are constantly changing both as to temperature and humidity, it is usually found that ordinary window ventilation is not very satisfactory and is often accompanied by excessive draughts.

Health centres advocate the use of fresh air in living and sleeping quarters, and they further advise on maintaining the humidity of the air at desirable levels. Frequently householders expose pans of water adjacent open windows in the hope that the air will take up in suspension sufficient water to temper the air in the household. This is at best a very inefficient manner of augmenting the humidity of dry atmospheric air or of substantially lowering the temperature thereof by evaporation, and it is also unsightly in a home, so that the ultimate result is far from satisfactory.

I have made a careful study of the problem of air conditioning in houses so as to cool the air as by evaporation or to provide the proper combination of air with the required humidity to give satisfactory results in every day use.

In seeking a solution to this problem there are several fundamentals to be considered, namely the cost of installing and maintenance of an air conditioning device, the ready adjustment of the device to suit changes in atmospheric conditions and the accessibility of the device in a manner which provides for routine inspection and/or cleaning.

I have solved this problem by the construction of an air conditioning and humidifying apparatus which is readily adaptable for use in private homes, and is also highly efficient and easy to control, and further the apparatus is not costly to either install or to maintain.

One of the objects of my invention is to construct an air control device which can be efficiently operated at low cost to rectify air conditions which become either too warm, too dry or too moist within a household.

Another object of my invention is to regulate the supply of moisture to the air control device, thereby providing suitable atmospheric conditions within the precincts of the household.

A further object of my invention is to efficiently scrub the air on passage through the air conditioning device, so as to remove dust, pollen and/or other solid particles in suspension in the air, and also excess globules of moisture in suspension in the air, so delivering to the household, air in a condition best calculated to serve the purpose required of it.

Still another object of my invention is to provide a rotatable fluid distributor to which moisture may be fed

2

at a required rate by means of a water carrying ring mounted on the distributor.

A further object still of my invention is to construct an air control device which may be readily and advantageously positioned outside a building, freely accessible to atmospheric air, and with a manually operated control extending from the device to the interior of the building, and operable therefrom.

Another object still of my invention is to provide an automatic self adjusting water level control for the device, thereby assuring a uniform delivery of water to the air being circulated through my air control device.

Still a further object of my invention is to construct the air conditioning device with stacked screening and scrubbing members in a manner which permits of such members being removed for cleaning and/or replacement in a minimum of time and with a minimum of labour.

Another object of my invention is to provide an air conditioning device which may be operated under dry conditions or under moist conditions, to ensure that the degree of humidity in the conditioned air delivered to the household will be such as to provide a comfortable and healthful atmosphere in the household.

Other objects will be made clear as the specification develops.

So that the nature of my invention will be clearly understood I have illustrated an embodiment of the same which I shall describe in detail, but I wish it to be understood that I do not limit my invention to this specific structure or description, but reserve the right to modify the same within the scope of my appended claims.

In the drawings:

Figure 1 is an end elevation, partly sectional, of my air control device showing the location of the rotatable fan and water distributor and the superposed screening and scrubbing mechanism;

Figure 2 is a transverse section of my air control device taken on the line 2—2 of Figure 1, and looking in the direction of the arrows;

Figure 2A is a side elevation detail with part of the fan drive pulley broken away to show the skeleton spider bearing support and air inlet arrangement;

Figure 3 is a plan view of the lower portion of the housing or casing of my air control device showing the location of the water trough in the lower part of the housing or casing, the view being taken on the line 3—3 of Figure 2 and looking in the direction of the arrows;

Figure 4 is a side elevation of the housing or casing of my air control device showing the manually operable control rod for turning the air conditioner on or off, including the emptying of the water trough; and

Figure 5 is a side elevation of the housing or casing of my air conditioner showing an alternative mechanism for controlling the operation of the device together with the suspension and feeding of the water trough, by manipulation of a manually operated rod which may be set to permit of selectable dry or wet running of my air conditioner as may be found necessary or desirable.

Like characters of reference refer to like parts in the several figures of the drawings.

Referring to the drawings, A represents my air conditioning device comprising a housing or casing 10 which is formed like a hollow parallelopiped provided in its lower wall with an elongated opening 11, and from the lower lateral marginal edges Z-shaped brackets 12 depend, and these brackets are of substantial depth and in parallelism throughout their lengths.

Below the opening 11 a rectangular trough 13 is positioned, and this trough is formed on its upper open end with outwardly extending lateral flanges which coact with the Z-shaped brackets 12. The rear end of the trough

13 is hinged at 9, but the forward end of the trough is floating within the limits of the depth of the web of the Z-shaped brackets. The forward end of the trough is supported by a helical tension spring 15, the lower end 16 of which is attached to the trough 13 while the upper end is attached to an angle bracket 17 on an adjacent wall of the housing or casing 10.

By reference to Figure 3 of the drawings it will be seen that the opening 11 extends across a major portion of the width of the lower wall of the housing or casing 10.

A shaft 18 is rotatably mounted in bearings 7 in the lateral walls of the housing 10, each bearing being carried or supported by a skeleton spider formed in the wall of the housing to provide a solid mounting for the bearing yet affording a number of surrounding openings 10^a so that air may enter the housing through these spider openings. The shaft 18 carries preferably midway of its length a cylindrical fan and distributor 19, comprising a plurality of flat, elongated radially disposed blades 19^a extending substantially the full width of the interior of the casing 10 and secured at opposite ends to disks 19^b. A rigid feed ring 20 of greater diameter than the fan encircles this cylindrical fan and distributor, and the lower portion of the ring projects through the elongated opening 11 in the bottom of the housing and into the trough 13. The shaft 18 when rotated thus causes liquid to be raised by ring 20, and delivered to blades 19^a which blades act as a unitary member to produce a flow of air and to distribute uniformly the liquid delivered to them.

The ends of the shaft 18 project beyond the lateral walls of the housing 10, and on one of the ends a belt pulley 21 is firmly secured, and aligned with this belt pulley is a second belt pulley 22 mounted on the drive shaft 23 of an electric motor B which may be of conventional or variable speed type. And endless belt 24 operatively connects the two pulleys 21 and 22 so that on energizing the motor B, rotary motion is transmitted to the shaft 18 and to the distributor and fan 19 mounted thereon.

On the inner faces of the lateral walls of the housing 10 a plurality of angle brackets 25 are mounted, and the upper faces of these brackets lie in the same horizontal plane and are designed to operatively support a plurality of stacked screening and scrubbing members 26.

Each of the screening and scrubbing members 26 may be constructed of a porous material or may be metallic, plastic or of other suitable materials, each screen being provided with a plurality of small perforations or interstices which extend over the entire surface of the screen and scrubbing members. Each screen and scrubbing member 26 is formed with a plurality of V-shaped grooves which are arranged in parallel relation to each other and extend completely across the width and below the lower face of the screen.

It will be noted by reference to Figure 2 that the first and third screens or scrubbing members 26 are arranged with their V-shaped grooves 27 extending longitudinally of the housing 10, whereas the second and fourth screens or scrubbing members 26 of the stack are arranged with the V-shaped grooves 27 extending transversely across the interior of the housing 10.

The stack of screen and scrubbing members 26 is located above the cylindrical fan and distributor 19, and it will be seen that a plurality of pockets are formed between adjacent superposed screens or scrubbing members.

The upper end of the housing 10 is desirably removable to afford access to the screens 26, and this upper end is formed with a take off conduit C, through which conditioned air is discharged from the air control and conditioning device A.

A water inlet pipe 28 running adjacent to one of the walls of the housing 10 has its free end 29 feeding into

the trough 13, and intermediate of the length of this pipe a water discharge valve 30 of conventional form is located.

Co-acting with the valve 30 is an actuating arm 31 which is pivoted intermediate its length to the housing 10 by the pin 32, and one end of this arm is connected to the lower end of the tension spring 33, the upper end of which is attached to the housing 10.

The end 34 of the arm 31 remoted from the spring 33 is bent in arcuate form to overhang the trough 13 which is provided with a transverse bar 35 designed to co-act with the end 34 of the arm to open the valve 30 and so permit of water being fed into the trough 13. The bottom or lower wall of the trough 13 is formed with a valve seat 36 with which the needle valve 37 carried by the hinged leaf spring arm 38 coacts.

In Figure 4 the spring-urged arm 38 is seen in open position with the free end thereof projecting beyond the trough 13 and engaged by the lower end of a rod 39 which passes through and slidably engages the guides 40 and 41 carried by the housing 10. Between the guides 40 and 41, the rod 39 is provided with a fixed washer 42 located toward the lower end and a slidable collar 43 near its upper end.

A compression spring 44 encircles the rod 39 and is located between the fixed washer 42 and slidable collar 43, and a second compression spring 45 encircles the rod 39 and is located between the fixed washer 42 and the guide 40. A manually operable rod or suitable flexible member 46 is formed with an arm 47 on its upper end which is secured to the lower face of the slidable collar 43 resting on the upper end of the compression spring 44.

The upper side of the arm 47, connected to the end 35 of the manually operable rod 46, carries a suitably insulated electric contact 48 which co-acts with an electric contact 49 to control the electric circuit serving the motor B, so that on the movement of the rod 46 upwardly under the action of springs 44 and 45 the contacts 48 and 49 engage and so close the electric circuit to the motor B and thus actuate the fan and distributor 19. The electric circuit may be wired into or temporarily connected by a conventional plug and socket with a source of electrical energy (not shown).

The manually operated rod 46 is provided with a suitable latch 50 to retain the rod in any one of several positions, but when the rod 46 is disengaged from the latch 50, then the springs 44 and 45 automatically move the rod 46 into the position described above in which the contacts 48 and 49 are closed completing the motor circuit, and simultaneously with this closing of these contacts, the vertical movement of the rod 39 has separated from the spring-urged arm 38 first allowing the needle 37 to close on the valve seat 36 and also permitting the trough 13 to rise under action of its coil spring 15 so as to actuate the valve arm 31 against the action of its closing spring 33 so that the trough is filled by the water pipe 28.

When the air conditioning device A is in use, water is fed through the pipe 28 and the valve 30 and delivered to the trough 13 and as the water reaches a predetermined and desired level in the trough 13, then the tension spring 15 supporting the trough permits the front end of the trough to move downwardly while the rear end of the trough which is hinged at 9 remains in normal position. During this downward movement of the front end of the trough, the transverse bar 35 becomes disengaged from the end 34 of the arcuate arm 31, so permitting the valve 30 to close.

Simultaneously the variable speed motor B is in motion, and the fan and distributor 19 is rotated. During this rotation of the fan and distributor rotary motion is also transmitted to the ring 20, and as the lower end of this ring is immersed in the water in the trough 13, then

a film of water is carried upwardly by the ring and discharged on the distributor.

The air entering through the spider openings in the walls of the housing 10 is circulated by the fan and distributor 19, and on leaving the periphery of the distributor it is in contact with the water on the distributor, so that the air now carries globules of water in suspension. This moisture laden air is projected upwardly within the housing 10 whence the stream of moist air impinges on the lowermost of the screen and scrubbing members 26.

The moisture laden air passes through the orifices in the V-shaped grooves, and the larger globules of water are arrested and flow along the V-shaped grooves toward the edges of the screen. This separation of suspended water from the stream of air is repeated as the air passes through each successive screen or scrubbing member 26, and any water separated during this passage of the air through the screen flows along the respective V-shaped grooves towards the walls of the housing 10.

A film or curtain of water consequently flows downwardly from the peripheral edges of the screens 26 during the upward movement of the air through the orifices in the screens and scrubbing members, so that free moisture laden air cannot escape and rise upwardly around the peripheral edges of the screen and scrubbing members 26, but must pass through the perforations in these screens and scrubbing members.

During this passage of the air through the screens and scrubbing members, the substantial evaporation that occurs acts to lower the temperature of the air and any solid impurities in the air are arrested and carried towards the ends of the V-shaped grooves, and the film or curtain of water moving downwardly into the lower end of the housing or casing 10 carries these solid impurities, which are ultimately washed into the trough 13 and periodically flushed in the manner previously described. Thus it will be appreciated that the perforated scrubbing plates of the stack, through which air flow must pass, serve as a filter, water distributing spreader, flow directional baffles, and water arresters.

When it is desired to shut off the motor, the actuating rod 46 is drawn downwardly to the "off" position shown in Figure 4 with the projecting finger 46^a engaged in the central notch in the latch 50, whereby the contacts 48 and 49 are separated thus interrupting the electric circuit and just bringing the lower end of the rod into light or near contact with the valve arm 38 as it is supported by the upward pressure of spring 45 on the fixed washer 42.

Should it be desired to run the machine dry, the rod could be drawn lower so that the finger 46^a would engage the latch 50 below the position already described whereby the bottom end of rod 39 would cause the trough valve arm 38 to flex against its spring action and cause the trough to drain through the port 36, in which case the contact 48 would engage an alternative contact 49^a spaced suitably below the primary contact 49, whereby the motor would actuate the air circulating fan but no water would be thrown up by the ring 20 that would be running in a dry trough.

As the air conditioner A is mounted externally of a building and thus open to the outer atmosphere, then the humidity of the outer atmosphere will determine whether the air conditioner should be operated in a wet state by the addition of water, or if the air conditioner should be operated dry owing to the atmospheric air already containing sufficient moisture.

Since the rod 46 is operated from within the building on which the air conditioner A is installed, then this rod may if found desirable be constructed of a semi flexible or flexible member which would permit of the rod being easily led into the building.

Figure 5 shows a modification of the actuating mechanism which is shown in Figure 4.

In Figure 5, the housing 10 as already described is

provided with an opening 11 in the lower wall, and the Z-shaped brackets 12 depend from the lower wall. A trough 13 is hinged at one end, and the other end is floating, and the trough is provided with lateral flanges which co-act with the brackets 12.

A water supply pipe is also provided as hereinbefore set forth with a valve 30 and the free or delivery end of the water pipe depends into the trough 13. Likewise the valve 30 co-acts with the spring controlled lever 31 which is pivoted at 32. The spring 33 normally holds the valve 30 in closed position, but as the trough 13 when empty is moved upwardly around its hinged end 9, then the transverse bar 35 co-acts with the arcuate end 34 of the lever 31 to rotate the said lever in a clockwise direction against the action of the spring 33.

All the above elements are common to both forms of the invention and are shown in Figures 4 and 5.

However in Figure 5 a lever 60 is pivotally mounted intermediate of its length on the pin 61 carried by the housing 10. The arms of the lever are of unequal length and the longer arm may be moved around the pin 61 within the arc determined by the upper and lower stop members 62 and 63.

On the end of the longer arm of the lever a switch actuating arm 64 of dielectric material is mounted which co-acts with the diverging arms of the pivoted switch 65 which forms part of the electric circuit including the variable speed motor B. The longer arm of the lever 60 is connected by a flexible member 66 which is provided adjacent its lower end with a pair of oppositely disposed arms 67 which co-act with the latch 68.

The latch 68 is provided on diametrically opposite walls with recesses 69 and 70 with which the arms 67 may be selectively engaged to retain the lever 60 in a desired position. The flexible member 66 passes through a cylindrical guide 71 on the latch 68, and the free end of the flexible member terminates in a hand grip 72.

The upper end of a helical tension spring 73 is connected to the longer arm of the lever 60 intermediate of the length thereof, and the lower end of this spring is of a rigid rod like formation and co-acts with the mechanism which controls the engagement or disengagement of the valve 37^a with the valve seat 36^a.

The shorter arm of the lever 60 is connected to the upper end of a helical spring 74, while the lower end of this spring is attached to the housing 10.

When a pull is applied to the hand grip 72 to engage the arm 67 with the recess 69, then the lever 60 is in a position between the stop members 62 and 63, and the spring 73 then operates the valve 37^a to disengage it from the valve seat 36^a so permitting the water to be drained from the trough 13 in the same manner as was described with respect to Figure 4.

As the water drains from the trough 13, then the transverse member 35 on the trough is disengaged from the end 34 of the valve lever 31, and the spring 33 attached to the end of the lever 31 tends to rotate the lever in an anticlockwise direction, so that the valve 30 is maintained in a closed position. This is for the "Dry run" operating of the device. Under the above circumstances the air conditioning device A is operated in a dry state. When it is desired to stop the machine, the hand grip 72 is pulled downwardly until the arm 67 engages the recess 70, the switch actuating arm 64 will rock the switch 65 to open the electric circuit, and shut off the motor B.

To restart the air conditioner, the hand grip 72 is actuated to disengage the arm 67 from the recess 70 and rise past the opposite recess 69, this permits the lever 60 to rotate in a clockwise direction under the action of the spring 74, and then the valve 37^a is closed on the valve seat 36^a by the pull of the spring 73. The trough 13 is rotated upwardly around its hinged end, and so the transverse bar 35 on the trough engages the end 34 of the lever 31 to rotate it in a clockwise direction against the action

of the spring 33. This movement of the lever 31 permits the valve 30 to open and deliver water to the trough 13 through the pipe 28. Simultaneously the lever-carried arm 64 teeters the pivoted switch 65 in circuit closing position setting the motor in operation.

When the water in the trough has reached the desired predetermined level, then the free end of the trough 13 is rotated downwardly around the hinged end of the trough and the air conditioning device A is operated under wet conditions.

It will be understood that as the water in the trough is used up, then the water level in the trough will fall below the desired, or permitted, lowest position so that the free end of the trough will be moved upwardly under action of the spring 73 to bring the transverse member 35 into engagement with the end 34 of the lever 31 thus causing the valve 30 to be actuated to replenish the water in the trough, and so bring it to the desired predetermined level.

From the foregoing description taken in connection with the accompanying drawings, it will be manifest that an air conditioner is provided that will fulfill all the necessary requirements of such a device, but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention, what is claimed as new is:

1. An air conditioner selectively operable in wet or dry condition comprising a housing having an air inlet and an air outlet, a unitary fan and distributor rotatably mounted in the housing adjacent the air inlet, air screening and scrubbing means between the fan and distributor and the air outlet, a constant level water trough movably suspended below said housing, manually operated means determining the dry or wet running of the air conditioner, and means responsive to the last said means to automatically cut off or deliver liquid from the trough to the distributor during the operation of the air conditioner.

2. An air conditioner comprising a housing having an air inlet and an air outlet and provided with an elongated opening in its bottom wall, a constant level water trough disposed below the housing and in registry with said opening, a unitary fan and distributor rotatably mounted in the housing adjacent the trough, means for feeding water from the trough to the distributor to humidify the air discharged by the fan during rotation of the fan and distributor, means between the distributor and the air outlet and in the path of the air discharged by the fan to remove excess water and suspended impurities from the air prior to discharge of the air through the air outlet.

3. The air distributor claimed in claim 2 in which the

means for feeding water to the distributor consists of a rigid ring encircling and concentric with the distributor, with the lower portion of the ring immersed in the water in the underlying trough.

5. The air conditioner claimed in claim 2 in which the means for removing excess moisture and suspended impurities from the air consists of at least one screen removably supported in horizontal position in said housing above said distributor.

10. The air conditioner claimed in claim 4 in which the screen is formed with a plurality of parallel V-shaped grooves extending wholly across the width of the plate.

15. The air conditioner claimed in claim 2 in which the means for removing the excess water and suspended impurities from the air consists of a plurality of perforated plates each formed with V-shaped grooves extending completely across the plate, the several plates being arranged in stacked relation with the V-shaped grooves of one plate disposed at right angles to the V-shaped grooves in an adjacent plate.

20. An air conditioner comprising a housing having an air inlet and an air outlet and a slotted lower wall, a water trough hinged at one end to the lower wall of the housing and disposed below and in registry with the slot, the other end of the trough being resiliently suspended from the housing, a unitary fan and distributor rotatably mounted in the housing above the trough, means actuated by the movement of the trough controlling the supply of water to the trough, means operating through said slot for feeding water from the trough to the distributor and means in the path of the stream of moisture laden air created by said fan and distributor for the removal of excess moisture and suspended matter in the air before delivery of the conditioned air to the air outlet.

25. The air conditioner claimed in claim 7 in which the trough is provided with a water outlet valve and remote manually actuated means to control the operation of the outlet valve.

30. The air conditioner claimed in claim 7 in which Z-shaped brackets of substantial depth are secured adjacent the lateral edges of the slot in the bottom of the housing, the bracket depending from the lower face of the bottom wall of the housing, and the trough being formed with outwardly disposed flanges to co-act with the Z-shaped brackets, thereby limiting the hinging movement allowed said trough to the vertical depth allowance of said brackets.
